HYDRATOR FOR LIME AND THE LIKE

Victor J. Azbe, Webster Groves, Mo., assignor to Azbe Corporation, Clayton, Mo., a corporation of Missouri

Application April 5, 1952, Serial No. 280,827

9 Claims. (Cl. 23—287)

This invention relates to hydrators for lime and the like, and more particularly to automatic continuously recycling apparatus of this type.

Among the several objects of the invention may be noted the provision of an automatic lime hydrator which will produce a consistently good hydrated lime from either good or poor raw material (quickslime); the provision of a hydrator of the class described which operates continuously without excessive attention, and without the escape of such quantities of dust and steam as ordinarily constitute a hazard or nuisance and loss in connection with apparatus of this class; and the provision of apparatus of this class which conveniently lends itself to instrumental control. Other objects will be in part apparent and in part pointed out hereinafter.

The invention accordingly comprises the elements and combinations of elements, features of construction, and arrangements of parts which will be exemplified in the structures hereinafter described, and the scope of which will be indicated in the following claims.

In the accompanying drawings, in which one of various possible embodiments of the invention is illustrated,

Fig. 1 is an isometric view of a hydrator embodying the invention, parts being broken away;

Fig. 2 is a right-end view of Fig. 1;

Fig. 3 is a left-end view of Fig. 1;

Fig. 4 is a top plan view of Fig. 1;

Fig. 5 is a diagrammatic sectional assembly view, parts being rearranged for clarity, with flow lines illustrating certain improved functions; and,

Fig. 6 is a cross section taken on line 6—6 of Fig. 5.

Similar reference characters indicate corresponding parts throughout the several views of the drawings.

Briefly, the invention consists in a container into which premixed quicklime and water are fed. This container has an adjustable discharge opening for maintaining an inside level of material. The container, which is preferably circular, has a bottom which slopes from the periphery toward a central annular portion for gravitating heavier granular material toward said central portion. The central portion is preferably flat.

Within the container is a rotor composed of a system of depending circular baffles having overflow slots in their sides. These slots allow progress of lighter hydrated material from the center toward the periphery and to said discharge opening. The baffles have lower plows arranged to bias the heavier granular material toward the flat central portion. Below the central portion is a waste discharge device. A partial vacuum is induced in the container in order to draw in air for cooling and delivery with generated steam and dust to a wet dust collector wherein the steam is partially condensed and the dust removed from the air. If desired, the air-vapor stream may be returned to the bottom of the circular container to provide additional control over the conditions, such as rate and temperature of hydration.

Referring now more particularly to the drawings, the circular container is shown at numeral 1, being mounted upon standards 3. It has a circular periphery 5 and a cover 7. Its bottom has a flat central annular sump portion 9 and a conical periphery forming an inward and downward slope 11. Centrally there is a cylindrical dam 13. Through this dam and the cover 7 extends a drive shaft 15 which is driven through a gear-reduction unit 19 by a motor 17. For example, the shaft 15 may be rotated on the order of 10 R. P. M., although this is not to be taken as limiting.

The motor 17 and reduction unit 19 are mounted upon a superstructure 21, carried upon standards 23. Suspended from the superstructure 21 is a premixer 25, constituted by a trough 27 in which are shafts 29 carrying interdigitating mixing paddles 31. The shafts are connected for 1:1 rotation by meshed gears 33. One of the shafts is driven from a motor 35 through a gear-reduction unit 37 and a chain drive 39. At 41 is shown an inlet opening for the premixer 25 and at 43 an opening leading to the container 1. At 45 is shown an inlet hopper for raw material (granular quicklime) from which the material is moved to the inlet 41 by means of a belt conveyor 47. The conveyor is driven from a motor 49 through a belt drive 51 and a gear-reduction unit 53. The function of the premixer 25 is to advance the raw material from the inlet 41 to the opening 43 of the container 1 and thoroughly to premix it with water. Water is introduced through nozzles shown at 55 and 56 (Fig. 5).

Attached to the rotary shaft 15 inside of the container 1 is a rotor or stirrer 2 constituted by a hub 57 from which extend radial arms 59, these arms supporting depending circular baffle plates numbered 61, 63, 65 and 67, progressing outward from the center. The lower circular rims of these baffles are near (but spaced from) the bottom parts 9 and 11. The inner baffle plate 61 is not perforated. Baffles 63, 65 and 67 are perforated by spaced and essentially rectangular openings 69, 71, 73, respectively. There are four openings 69, each 31 inches long and 16 inches high. There are eight each of openings 71 and 73, each 36 inches long and 10 inches high. The lower edges 68 of openings 69 are below the lower edges 72 and 74 of openings 71 and 73, respectively. On the lower rims of the baffles 61, 63, 65 and 67 are groups of angled plows 75, 77, 79 and 81. The inner plows 75 are angled to push particles outward, whereas the plows 77, 79 and 81 are angled to push granular material inward. The plows are adjustable in angle and height (see set screws 82 in Fig. 1 for this purpose).

The container 1 has an overflow outlet 83, the lower edge of which is on and controlled in elevation by a vertically sliding gate 85. A typical level of material in the container 1, as determined by gate 85, is indicated at L. Exit takes place into a hopper 87, which directs finished hydrate to storage. At 89 is shown an outlet gate for periodically discharging material from the bottom 9 of the container 1. This is on a shaft 90 supported by a bracket 92 and operated by a lever 94. Suitable access openings for the container 1 are shown at 91, and an inspection door at 93.

While it is preferable that the container 1 and baffles 61, 63, 65 and 67 be circular and concentric, it is to be understood that this is not a necessary feature, since they may be relatively eccentric, or suitably polygonal. It is also to be understood that while the particular shapes indicated in the bottom parts 9 and 11 are preferable, other shapes may be employed for these without departing from the invention.

At 95 is shown a wet dust separator or collector of the centrifugal type having an air outlet 97 in which is a damper 99. Its inlet is shown at 101 (Fig. 4), to which is connected the outlet of a centrifugal blower 103. The blower is driven from a motor 104 through a belt drive 106. The inlet of the blower 103 is connected with the top 7 of container 1 by means of an induction pipe 105. In the induction pipe 105 at the inlet of blower 103 is a water sprayer 107. At the bottom of the collector 95 is a water-condensate pump 109 (driven from motor 116) which collects warm water and entrapped dust from the separator 95 and through suitable piping 110 may deliver it to inlets 56, 55 and to an additional water inlet 112 in container 1. It will be understood that cold water may be supplied to 56, 55 and 112 over a line 114.

Since a large amount of steam is generated in the process, it cannot all be condensed by any reasonable amount of water injected at 107. However, if sent to atmosphere through the pipe 97, dust free, it is not objectionable. Also, some of it may be sent over a line 121 to a circular header 123 having inlets 125 to the bottom 11. This is accomplished by adjusting the damper 99 toward a closed position. The result is

that additional moisture is introduced into the container 1 at a point to air bind or otherwise condition the bed.

Operation is as follows:

Raw material is introduced into the hopper 45 in the form, for example, of granulated quicklime crushed to a grain size of the order of $\frac{1}{8}$ to $\frac{1}{4}$ inch and including whatever fines occur in the crushing process. Such material may vary in quality, such as being soft burned, hard burned, and having more or less core and extraneous material. Some parts of this material require a longer time for hydration than other parts. The material progresses along the belt 47 through the inlet 41 to the premixer 25. Water is supplied through inlets 56 and 55. Premixing occurs, the water being gradually taken up as water of hydration. The premixed material with water enters the container 1 through the opening 43, the hydrating process continuing in the container with the generation of considerable heat and escape of steam and some dust. More water may be applied through inlet 112. The inlet is positioned to drop the water near the center of container 1, where the larger granules exist. As hydration progresses, the granular material progressively disintegrates into finer particles and it is desired to have these in as powdered, light and flocculent a state as possible for highest quality of product. This result is encouraged because the smaller, lighter and more flocculent particles tend to rise, whereas the remaining granular particles that exist at any instant tend to settle to the bottom 9, 11 with the aid of paddle-created downward suction which tends to overcome the carrying viscosity of the fine hydrated lime travelling laterally toward the outlet. The downwardly pointed arrows 113 indicate the tendency for the heavy granular and less hydrated material to descend. The smaller sized material tends to rise, as shown by arrows 115. The paths of the heaviest granules are indicated by the lower arrows 117, and the path of the lightest and most completely hydrated material, which is in a finished flocculent state, is indicated by arrows 119. The heaviest material 117 gravitates down the sloping sides of the container under the baffles and is aided in moving toward the center by the plows 77, 79 and 81. As this heavier material arrives at the bottom 9, it is met by the outwardly directing plows 75. Thus the most granular and least hydrated material is retarded from advance toward the outlet and recycled for additional agitation and hydration, whereas the lighter, completely hydrated particles gradually rise and progress through the openings 69, 71 and 73 to the outlet 83. The result is that any part of the product which is in a finely finished state escapes, without being subjected to an undue additional heating which tends to spoil it; whereas the portions of the raw material which are more recalcitrant to hydration and require more time are retained until hydration is substantially completed. Stirring occurs of a minimum amount of the unhydratable portions, which are near the bottom. This is an advantage, since no more than a necessary amount of stirring should occur in these portions to prevent forcing them up into the good hydrate which is above. The gate 85 is adjusted so that the level L is at an optimum value for obtaining a maximum amount of best product. The result is not only a better hydrated lime but, by means of the invention, a greater percentage of hard burned material is converted. When core and other unhydratable material is present, such as is granular, it accumulates and is removed at gate 89 in timed periods dictated by the rate of accumulation, this being from one to eight hours.

During the above-mentioned circulation and hydration, a large amount of steam and some dust are evolved. These are drawn off by the induction blower 103, fresh air acting as a coolant entering the openings such as 43 and 83 and of course at any other points of infiltration or leakage into the container 1. The entry of this cool air provides a controlled atmosphere at level L for preventing overheating. Moreover, steam and dust are drawn off and subjected to the cold water spray at nozzle 107. The blower 103 thoroughly intermixes this spray with the steam and dust. The dust is entrapped with the condensate, while air and the remaining steam may leave the exhaust pipe 97 to the extent that the damper 99 is open. In the outside atmosphere the steam is harmless, whereas if it were to escape in the environs of the container 1 it would constitute a nuisance.

The dust-laden condensate may be sent to waste or is transferred over pipes 110 to the nozzles 56, 55 and 112 for supplying preheated moisture. Under some, although not all circumstances, it may be desirable to apply additional moisture to the granulated material on the bottom 9, 11 without applying additional moisture to the flocculent material in the region of the level L. In this event line 112 may be closed at valve 127 and the damper 99 adjusted toward closed position, thus forcing air and any noncondensed steam back through pipes 121 and into the openings 125. This steam supplies additional water hydration precisely where needed, i. e., in the bottom of the container 1.

Advantages of the invention over both prior batch and continuous type hydrators are as follows:

(1) The device has the classifying feature whereby the finely divided dry finished hydrated part of the product is advanced or "floated" to the outlet, while the more granular unfinished and heavier parts are retained and recycled until properly finished, or ejected to waste. In other words, the parts of the raw material which can be quickly finished are promptly removed from the process, whereas those parts which require more time for finishing are retained. Moreover, those parts that can practically never be finished can be removed through the separate discharge 89. The result is a greater production rate of better hydrated lime from any type of raw material (quicklime).

(2) The controlled atmosphere and recirculation of air-vapor mixture to the bed has the further action of controlling the vapor absorption and vapor supply, using air in its relative and controllable amount as an inhibiting medium.

(3) The preheating of water to the premixer initiates a more rapid prehydration.

(4) The wet dust collector system with the positive induction means for preventing escape of steam around the container 1 reduces the nuisance, health and accident hazards ordinarily associated with equipment of this type, and recovers all of the dust which is the best hydrate.

(5) The controlled atmosphere and recirculation of air-vapor mixture to the bed, mentioned under advantage (2), is easily obtained by control of the damper 99. When this damper is closed, a larger proportion of steam enters the pipes 125 because the fan 103 is incapable of introducing much air into the circulating system under such conditions. When the damper 99 is opened, then more air is in circulation and a larger proportion of air is available at ports 125. This control is an advantage, since it is sometimes as important to inhibit the hydrating action by introducing a substantial amount of air into the hydrating lime, which has a binding effect, preventing an excessive rate of hydration. As a large proportion of air is introduced at 125, the reaction is inhibited, resulting in lower capacity but a better hydrate for certain purposes, although not necessarily for others. Thus plasterers demand a special plastic hydrate which is better formed at a lower reaction rate. Another feature in this connection is that the single fan 103 is capable of effecting the desired circulation and with a simple damper 99 there is obtained a regulation of the air-steam proportions.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

I claim:

1. A hydrator for lime and the like comprising a container having a bottom and a higher outlet for hydrated material, inlet means for introducing granulated material and water into said container, and a rotor in the container having depending baffles each formed to surround the center of rotation, said baffles having elevated passage means for radially forwarding lighter hydrated particles toward said outlet and allowing the sinking between baffles of heavier nonhydrated particles toward the bottom, said baffles having lower edges spaced from said bottom and inwardly acting plowing means connected with some of said lower edges and adapted to push heavier nonhydrated particles that are at said bottom toward the

center of rotation of the rotor, whereby said heavier particles are recirculated for longer treatment than said lighter particles.

2. Apparatus made according to claim 1, including a premixer in said inlet for the granulated material and water, a wet dust collector, means for abstracting air, dust and steam from said container and delivering it to said collector, means for introducing a water spray into said abstracting means to wet the dust and condense some but not all of said steam, including means wherein water including condensate from the collector is introduced into said premixer, and including means for returning air and uncondensed steam in regulatable proportions from said collector to the bottom of said container.

3. A hydrator for lime and the like comprising a circular container having a peripherally located elevated outlet for hydrated material, means for introducing granulated material and water into said container, said container having a conical bottom sloping inward and downward toward its center, a rotor in the container having depending circular baffle plates above said conical bottom, said baffle plates having elevated passage means for radially forwarding lighter hydrated particles directly toward said outlet, certain of said baffle plates having peripherally spaced plow means on their lower edges adapted to 25 influence movement of granules down the conical bottom toward the center of rotation to induce a recycling action in respect to heavier less-hydrated particles.

4. Apparatus made according to claim 3, wherein said container has a waste discharge outlet in its bottom adjacent the center of rotation.

5. Apparatus made according to claim 4, wherein said elevated outlet in the container has an adjustable overflow edge for adjustment of the level of material therein.

6. A hydrator for lime and the like comprising a circular container having a peripherally located outlet for hydrated material, means for introducing granulated ma- 35

terial and water into said container, said container having a bottom which on its outside is peripherally substantially conical and which forms a downward and inward slope so as to form a central sump, a rotor in the container having depending circular and concentric baffle plates, the innermost baffle plate extending toward the sump, said plate being unperforated and carrying at its lower end outward plowing elements in the sump, the remaining baffle plates having elevated perforations and carrying at their lower ends inward plowing elements adapted to push material down said slope.

7. Apparatus made according to claim 6, including means in said container providing a periodically operable waste-material outlet in said sump.

8. Apparatus made according to claim 7, wherein said waste-material outlet is located between groups of outward and inward plowing elements.

9. Apparatus made according to claim 8, wherein the means for introducing granulated material and water into the container is constituted by means located in such a position on the top of the container as to insert material at a location also between groups of outward and inward plowing elements.
